CLAIM

We claim the ornamental design for a bicycle sprocket assembly, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front perspective view of a bicycle sprocket assembly showing our new design;

FIG. 2 is a front view of the bicycle sprocket assembly shown in FIG. 1;

FIG. 3 is a rear view of the bicycle sprocket assembly shown in FIG. 1;

FIG. 4 is a left side view of the bicycle sprocket assembly shown in FIG. 1;

FIG. 5 is a top view of the bicycle sprocket assembly shown in FIG. 1;

FIG. 6 is a bottom view of the bicycle sprocket assembly shown in FIG. 1; and,

FIG. 7 is a right side view of the bicycle sprocket assembly shown in FIG. 1.

1 Claim, 7 Drawing Sheets
